(57) **CLAIM**

The ornamental design for a display screen or portion thereof with graphical user interface, as shown and described.

DESCRIPTION

The FIGURE is a front view of a display screen or portion thereof with graphical user interface of our new design. The thicker vertical dash-dot broken lines in the FIGURE at the Date and Patient Timeline panels illustrate parts of the graphical user interface that form part of the claimed design. The dash-dot-dot broken lines in the drawings illustrate the display screen or portion thereof that form no part of the claimed design. The remaining dash-dot lines illustrate portions of the graphical user interface that form no part of the claimed design.
